INVENTOR
JOSEPH BASILE
BY Charles Basile
ATTORNEY

UNITED STATES PATENT OFFICE.

JOSEPH BASILE, OF NEW YORK, N. Y., ASSIGNOR TO GREENPOINT METALLIC BED COMPANY, OF BROOKLYN, NEW YORK, A FIRM.

BED.

1,335,549.

Specification of Letters Patent. Patented Mar. 30, 1920.

Application filed July 11, 1919. Serial No. 310,106.

To all whom it may concern:

Be it known that I, JOSEPH BASILE, a subject of the King of Italy, and a resident of New York city, in the county of New York 5 and State of New York, have invented certain new and useful Improvements in Beds, of which the following is a specification.

The invention relates to improvements in metal beds and more particularly to improvements in what are commonly called three-piece beds, these comprising a head-frame, a foot-frame and a mattress or spring carrying frame intended for detachable connection with the head and foot-frames. My 10 invention has reference more particularly to the corner-fastenings by which the mattress or spring carrying frame may be properly and rigidly secured to the head and foot-frames, and resides more especially in novel 15 corner-fastening members secured to the side-rails of the spring or mattress carrying frame and which receive the end rails of said frame, and novel locking members connected with the corner-posts of the bedstead 20 and adapted to receive said corner-fastening members of the spring or mattress frame, the whole being so arranged, combined and constructed that a very substantial bedstead frame may be produced.

30 The invention will be fully understood from the detailed description hereinafter presented, reference being had to the accompanying drawings, in which:

Figure 1 is a central vertical longitudinal 35 section, partly broken away, through a corner-fastening embodying my invention, the side rail, a portion of the end-rail, a portion of the corner-post and a portion of the mattress being illustrated;

40 Fig. 2 is a horizontal section through the same, taken on the dotted line 2—2 of Fig. 1;

Fig. 3 is a top view, partly broken away and partly in section, of the same, the corner-post being the only portion illustrated 45 in section;

Fig. 4 is a perspective view of one of the main members of the corner-fastening, including a portion of the side rail of the bedstead;

50 Fig. 5 is a detached perspective view of a closing plate which, in use, I apply to the upper portion of the fastening member shown in Fig. 4, said plate closing the upper outer portion of the space between the sides 55 of said fastening member;

Fig. 6 is a detached perspective view of one member of the corner-fastening, this member comprising a loop which is inserted through the corner-post to receive a wedge and at its other portion affording flanges to 60 receive the right angle flanges shown on the corner-fastening member presented in Fig. 4:

Fig. 7 presents a perspective view of a portion of the end rail of a bedstead, this 65 end rail being of angle iron and adapted to receive the helicals for the mattress, and

Fig. 8 is a horizontal section, partly broken away, through the corner-post and a portion of the corner-fastening taken on the 70 dotted line 8—8 of Fig. 1.

In the drawings, 10 designates a portion of the corner-post of a metal bedstead, 11 a portion of one of the side rails thereof, 12 a portion of one of the angle iron end rails 75 of the bedstead, 13 the usual helicals connected with said end rail, and 14 a portion of the mattress or spring supported by said helicals from the end rail 12.

My invention has reference more particularly to means, commonly called a corner-fastening, for connecting the side-rails 11 and end-rails 12 to the corner-posts of the bedstead.

One member of the corner-fastening is 85 numbered 15, and the details of this member 15 are probably more clearly illustrated in Fig. 4. The member 15 is formed from sheet steel in one integral piece folded over upon itself to form a main loop 16, parallel 90 facing flanges 17 and parallel sides 18 whose upper portions are cut away, as at 19, to form the outwardly projecting tongues 20 and shoulders 21. The flanges 17 are riveted together by rivets 22 and the lower inner 95 portion of the loop member 16 receives the outer end of the side rail 11, whose extreme end brings up against a stop shoulder 23 formed by a lip pressed upwardly from the material at the lower side of said loop member, as shown in Fig. 1. The side-rail 11 is so closely bound within the inner end of the loop 16 that it cannot be withdrawn therefrom under any ordinary conditions.

The corner-fastening member 15 is formed 105 below the shoulders 21 with flat members of right angular outline comprising flanges 24 which are parallel with the corner-post 10 and flanges 25 which stand at right angles to said flanges 24 and project inwardly be- 110

tween the sides 18 of the corner-fastening end member 15, as clearly represented in Figs. 2 and 4. The corner-fastening member 15 is thus in one integral piece comprising the flanges 17, sides 18, tongues 20 and flanges 24, 25, this member 15 being in one integral piece and rigidly secured to the side rails 11 of the bedstead.

The corner-post 10 may be of any usual 10 or suitable construction, and at present I illustrate a post 10 which is of metal and rectangular in cross-section. The corner-post 10 is formed with a vertical slot 26, and on the inner face of said post adjacent to the fastening member 15 I apply a metal plate 27 having a corresponding slot 28, while upon the outer face of said post 10 I apply a further plate 29 having a slot 30 matching the slots in the plate 27 and corner-post 10.

The means for connecting the corner-fastening member 15 with the corner-post 10, comprises, in addition to the flanges 24, 25 of said member 15, the device shown in 25 Fig. 6, which is of sheet steel and embodies a loop member 31 formed by bending the metal of said device upon itself, shoulders 32 above and below said loop member 21 which engage the face of the plate 29 applied to the inner outer face of the post 10, and lateral flanges 33 which receive behind them the flanges 25 formed on the fastening member 15, as shown in Fig. 2. I preferably curve the metal of the fastening device 30 shown in Fig. 6 inwardly, at opposite sides, in the manner denoted at 34, so as to bring the sides of the loop member together inwardly beyond the post 10 and thus add rigidity to said member and also to provide 35 proper clearance for the flanges 25 of the corner-fastening member 15, when said flanges are slipped downwardly behind the flanges 33. The horizontal loop portion 31 of the fastening device member, shown in 40 Fig. 6, is, as clearly represented, introduced through the slots 26, 28, 30 of the post 10 and plates 27, 29 the shoulders 32 of said device bringing up against the plate 29, and the said device shown in Fig. 6 is rigidly 45 fastened to the corner-post 10 by means of an interior wedge bar 35 which is introduced downwardly through the interior of the corner-post and between the sides of said loop member 31 and driven firmly to position so as to draw the shoulders 32 of the locking device shown in Fig. 6 into rigid relation with the plate 29, thereby securing the locking members shown in Fig. 6 in rigid relation to said post.

50 In view of the offset formed by the shoulders 21 on the corner-fastening member 15 and the opening thereat and above the same between the sides of said member 15, I apply a plate 36, shown in Fig. 5, upon the 55 tongues 20 of the member 15, said plate hav-

ing an upper portion 37 containing slots 38 to fit upon said tongues 20 and a lower inclined portion 39 to engage the upper edges of said shoulders 21, said plate thus closing the space between the upper portions of the 70 sides of the fastening member 15. The plate 36 is not absolutely essential for the corner fastening, but is a valuable portion thereof in that it serves to exclude dust and the like from the space between the upper 75 portions of the sides of the member 15.

Upon the tongues 20 or those portions thereof which extend outwardly beyond the plate 36, I apply the end rails 12, said end rails being at their end portions provided 80 with slots 40 to pass upon the tongues 20 which may thereafter be upset, as shown in Fig. 1, to permanently connect the rails 12 to the corner-fastenings, and thereby produce what is in effect a three-piece bed comprising the head and foot frames and the mattress or spring carrying frame consisting of the side rails 11 and fastening members 15. The end rails 12 are apertured, as at 41, to receive the helicals 13 of the mattress or spring 14, as usual. The presence of the end rails 12 on the tongues 20 serve to effectually secure the protector plates 36 in permanent and rigid position.

In assembling the several parts of the 95 bedstead, after the fastening members shown in Fig. 6 have been secured to the corner-posts and the corner-fastening members 15 have received the side-rails 11, end rails 12 and mattress or spring, the fastening-members 15 are moved against the corner-post 10 and the flanges 25 of said members 15 are slid downwardly behind the flanges 33 of the locking device, shown in Fig. 6, or to the position shown in Figs. 1 and 2, the flanges 100 24 of the member 15 at that time sliding downwardly against the outer face of the plate 29, which is a reinforcing plate, and in the absence of which said flanges 24 will slide downwardly along the exposed face of 105 the corner-post 10.

One important feature of the invention is that the flanges 33 of the fastening device shown in Fig. 6 incline downwardly and outwardly so as to afford inclined or wedge 115 surfaces, and that the inner edges of the flanges 25 incline downwardly and outwardly so as to afford wedge surfaces, as indicated by the dotted lines in Fig. 1. When, therefore, the corner-fastening member 15 120 is applied to the corner-post and the flanges 25 are caused to settle down behind the flanges 33, there is a wedging action between the fastening member 15 and the locking-member shown in Fig. 6 which serves to 125 very rigidly connect that member of the bedstead which includes the side rails and spring or mattress, with the corner-posts of the head and foot-frames of the bedstead.

The corner-fastening of my invention, as 130

shown in the drawings, is duplicated at the four corners of the bedstead and therefore it seems to be sufficient to show these devices as applied to one corner of the bedstead.

5 The parts composing the corner-fastening are few in number and of great efficiency and durability. With the employment of said corner-fastenings, the member comprising the spring, end members and side rails

10 may be very quickly and conveniently applied to the end frames and when applied the bed frame as a whole is very rigid and devoid of rocking or loose movement, the head and foot-frames being held in rigid

15 vertical position with relation to the middle member of the bed consisting of the mattress or spring, side rails and fastening members 15.

What I claim as my invention and desire 20 to secure by Letters-Patent, is:

1. In combination with a side-rail and a corner-post of a bedstead, a corner fastening therefor comprising a sheet metal member embracing the end of the side-rail and 25 having parallel sides secured together along one edge and at their outer edges formed with spaced-apart corresponding right-angle vertical flanges, the outer of whose members face the corner-post while the other

30 members extend inwardly between said sides, a locking-member having a loop extended into the corner-post, shoulders facing the said post and laterally extending flanges to receive behind them the inwardly extending 35 members of said right-angle flanges, and means for securing said locking-member to the corner-post.

2. In combination with a side-rail and a corner-post of a bedstead, a corner fastening 40 therefor comprising a sheet metal member embracing the end of the side-rail and having parallel sides secured together along one edge and at their outer edges formed with spaced-apart corresponding right-angle vertical flanges, the outer of whose members face the corner-post while the other members extend inwardly between said sides, a locking-member having a loop extended into the corner-post, shoulders facing the said 45 post and laterally extending flanges to receive behind them the inwardly extending members of said right-angle flanges, and means for securing said locking-member to the corner-post, said inwardly extending 50 members being at their free edges inclined downwardly and outwardly and said laterally extending flanges of said locking-member being inclined downwardly and outwardly so as to establish a wedging-action between these parts.

3. In combination with a side-rail, a corner-post and an end-rail to receive the spring or mattress member of a bedstead, a corner-fastening therefor comprising a 55 sheet metal-member embracing the end of

the side-rail and having parallel sides secured together along one edge and at their outer edges formed with spaced-apart corresponding right-angle vertical flanges, the outer of whose members face the corner- 70 post, while the other members extend inwardly between said sides, and said sides also being cut away above said right-angle flanges to form tongues and shoulders, a locking-member having a loop extended 75 into the corner post, shoulders facing said post and laterally extending flanges to receive behind them the inwardly extending members of said right-angle flanges, means for securing said locking member to the 80 corner-post, and a closing-plate having slots to pass upon said tongues and upper and lower members to close the space between the upper outer portion of said parallel sides, said end-rail being slotted to pass 85 upon said tongues.

4. In combination with a side-rail, a corner-post and an end-rail to receive the spring or mattress member of a bedstead, a corner-fastening therefor comprising a 90 sheet metal-member embracing the end of the side-rail and having parallel sides secured together along one edge and at their outer edges formed with spaced-apart corresponding right-angle vertical flanges, the 95 outer of whose members face the corner-post, while the other members extend inwardly between said sides, and said sides also being cut away above said right-angle flanges to form tongues and shoulders, a 100 locking-member having a loop extended into the corner post, shoulders facing said post and laterally extending flanges to receive behind them the inwardly extending members of said right-angle flanges, means for 105 securing said locking member to the corner-post, and a closing-plate having slots to pass upon said tongues and upper and lower members to close the space between the upper outer portion of said parallel sides, 110 said end-rail being slotted to pass upon said tongues, said inwardly extending members of said right angle flanges being at their free edges inclined downwardly and outwardly, and said laterally extending flanges 115 of said locking member being inclined downwardly and outwardly so as to establish a wedging-action between these parts.

5. In a bedstead frame, in combination, a side rail, a corner-post and an end rail 120 to receive the spring or mattress member, a corner-fastening therefor, comprising a sheet metal member secured to the end of the side-rail and having parallel sides secured together along one edge and at their outer edges formed with spaced-apart corresponding right-angle vertical flanges, the outer of whose members face the corner-post, while the other members extend inwardly between said sides, and said sides 125

65 sheet metal-member embracing the end of

also being cut away above said right-angle flanges to form tongues and shoulders, a locking-member having a loop extended into the corner-post, shoulders facing said post and laterally extending flanges to receive behind them the inwardly extending members of said right-angle flanges, a plate at the inner side of said post through which said loop extends, a plate at the outer side 10 of said post through which said loop extends and which is engaged by the shoulders of said locking member, a wedge within said post entered through said loop and engaging said plate located at the inner

side of said post, for securing said locking member to the post, and a closing-plate having slots to pass upon said tongues and upper and lower members to close the space between the upper outer portion of said parallel sides, said end rail being slotted 15 to pass upon said tongues.

Signed at Brooklyn, in the county of Kings and State of New York, this seventeenth day of June, A. D. 1919.

JOSEPH BASILE.
